UNITED STATES PATENT OFFICE.

FRANK KARSCHITZ, OF BRIDGEPORT, CONNECTICUT.

COMBINATION-CHAIR.

1,353,595.

Specification of Letters Patent. Patented Sept. 21, 1920.

Application filed September 12, 1919. Serial No. 323,370.

To all whom it may concern:

Be it known that I, FRANK KARSCHITZ, a subject of the Republic of Hungary, residing at Bridgeport, county of Fairfield, 5 State of Connecticut, have invented an Improvement in Combination-Chairs, of which the following is a specification.

This invention relates to the class of chairs illustrated and described in Patent No. 10 1,305,221, granted to me May 27, 1919, and has for its object to generally improve the 15 details of construction and to especially adapt the chair *per se* for use either in connection with an infant's high chair or go- 20 cart or with a steamboat or invalid chair as well as for use in connection with a swing- 25 ing chair.

With these and other objects in view I 25 have devised the novel combination chair 20 which I will now describe referring to the accompanying drawing forming a part of this specification and using reference characters to indicate the several parts.

Figure 1 is a perspective view showing the 30 members adjusted for the sitting position, the back being up, the leg and foot rests down, and the table in the horizontal position;

Fig. 2 a side elevation showing the leg 35 rest raised without raising the foot rest and the table shifted to a position to serve as a reading desk, and

Fig. 3 is an elevation showing the members adjusted to the reclining position.

35 It should be understood that the chair is adapted without change in its structure to any of the uses above referred to. By attaching an axle, wheels, and a handle to a small sized chair it becomes an infant's go- 40 cart. By attaching legs it becomes a high chair, or by attaching legs to a larger sized chair it becomes an invalid or steamboat chair, or by attaching it to the structure illustrated in my said patent it becomes a 45 swinging chair or hammock.

10 denotes the seat, 11 the back, 12 the leg rest, 13 the foot rest, 28 the arms, and 14 the table. The back is pivoted, as at 16, to the side strips of the seat, indicated specifically by 15. The side strips of the foot rest, indicated specifically by 17, are pivoted outside the side strips of the seat on a cross rod 18. Side strips 17 are extended above their pivotal points and are connected to the 55 side strips of the back, indicated specifically by 19, by links 20 which lie substantially

parallel with side strips 15 of the seat. These links perform their usual function in a reclining chair and cause the back and foot rest to swing in unison, the foot rest swinging upward when the back is swung downward, and vice versa. The back and foot rest may be locked at any desired inclination by means of a curved rack 21, one end of which is pivoted to one of the side strips of 60 the back, the other end sliding through a keeper 22 secured to the corresponding arm. The leg rest comprises side strips 23, which are pivoted concentrically with the foot rest on cross rod 18 on the inner side of the side 65 strips of the seat, and cross strips 24. The leg rest is retained at any required adjustment by means of a suitable connection, as curved rack 25, one end of which is pivoted to a side strip 23, the other end sliding 70 through a keeper 26 which is secured to the corresponding side strip 17 of the foot rest. For invalid chairs the leg rest may be made in two parts, each provided with a curved 75 rack, so that either part may be raised independently of the other.

It will be noted that while the leg rest may be raised independently of the foot rest, raising of the latter will carry the leg rest with it. The table is pivoted, substantially as in my said patent, to side strips 27, the rear ends of which are pivoted to the arms by means of pins 30. It is an important feature of the present structure that side strips 27 are so connected to the arms 80 that when it is desired to swing the table from the position shown in Fig. 1 to that shown in Fig. 3, that is from the position in which it is used as a table to that in which it is used as a head rest, side strips 27 may 85 be slid forward so as to enable the table to be swung backward over the head of a person occupying the chair without the necessity of the occupant bending his head forward, it being understood of course that 90 when used as a table the member must rest close to the occupant in convenient position for use. In order to accomplish this result I provide plates 29 which are secured to the arms, each plate being provided with an inwardly extending pin 30. These pins project through slots 31 in side strips 27. The weight of the table and side strips 27 is 95 supported by means of brackets 32 secured to the arms near their forward ends. These 100 brackets are provided with bayonet slots 33 which are engaged by pins 34 extending in-

ward from side strips 27. When in use as in Fig. 1, the table is swung forward until the pins lie in the horizontal portion of the slots which prevents the table from being raised by a child, when used on a high chair. To swing the table over backward to the position shown in Fig. 3, pins 34 are disengaged from the slots, then the table is moved forward until pins 30 lie at the rear ends of slots 31 in which position the table, when swung over backward, will easily clear the head of an occupant of the chair.

- Having thus described my invention, I claim:
- 15 1. In a chair the combination with a seat having arms provided near their rear ends with pins and near their forward ends with brackets, a back and a foot rest pivoted to the respective ends of the seat, and links

connecting the back and the foot rest, of a 20 table, and side strips therefor having sliding pivotal connection on said pins, the weight of the side strips and the table being supported by the brackets.

2. In a chair the combination with a seat 25 having arms provided near their rear ends with pins and near their forward ends with brackets having bayonet slots, a back and a foot rest pivoted to the respective ends of the seat, and links connecting the back and 30 the foot rest, of a table, and side strips therefor having near their rear ends slots through which the pins on the arms pass, and pins adapted to engage the bayonet slots in the brackets.

In testimony whereof I affix my signature.

FRANK KARSCHITZ.
